UNITED STATES PATENT OFFICE.

EDWARD S. PRESTON, OF CHICAGO, ILLINOIS, ASSIGNOR TO EDMUNDS & JONES CORPORATION, A CORPORATION OF NEW YORK.

LEVER SWITCH.

Application filed June 21, 1922. Serial No. 569,962.

To all whom it may concern:

Be it known that I, EDWARD S. PRESTON, citizen of the United States, residing at Chicago, in the county of Cook and State 5 of Illinois, have invented certain new and useful Improvements in a Lever Switch; and I do hereby declare the following to be a full, clear, and exact description of the invention, such as will enable others skilled 10 in the art to which it appertains to make and use the same.

My invention relates to electrical appliances and in most of its general aspects relates to an electric switch construction 15 designed for affording an easily constructed, inexpensive, compact and handsome switch. Furthermore, my invention includes as one feature a cheaply manufactured and advantageously formed conducting member 20 adapted to afford an unmarred thread for engaging a binding screw.

More particularly, my invention relates to an electric switch in which the switching member continuously engages one circuit 25 terminal and is adapted to be moved into and out of engagement with the other circuit terminal. For this purpose, my invention aims to provide an inexpensive and advantageously arranged mounting for both 30 circuit terminal members and one in which one of the latter has a portion guiding the contacting part of the switching member and desirably formed for cooperating with suitable spring means in yieldingly latching the switching member either in its "on" 35 or its "off" position. It also aims to provide a construction for this purpose in which the constituent parts can readily be made and assembled by simple punch-press and 40 screw-machine operations, and in which the circuit-closing contact can be made directly to a conducting member into which one of the wire binding screws is threaded.

In a further aspect, my invention aims 45 to provide a switch of a rocking lever type, aims to provide a yielding extensible lever member and one in which the contact tip is suitably insulated from the handle end of the lever and in which the various portions of the lever member can easily be assembled 50 without employing auxiliary fastening elements.

Furthermore, my invention aims to pro-

vide a switch of the rocking lever type in which the pivotal support for the lever is 55 afforded by a suitable formation in one wall of the casing without requiring any shaft or auxiliary supporting member, and in which the lever is retained in its operative position by the mere assembling of the casing. It also aims to provide a switch of the rocking lever type in which the mounting of the lever would permit a movement 60 of the latter in various planes, and aims to provide suitable guide means for limiting 65 the movement of the lever to a single plane. Furthermore, my invention desirably aims to provide such guide means as an integral part of one circuit terminal member, desirably aims to form this part so that its 70 shape will cooperate with the movement of the lever past the center of travel thereof in holding the contacting portion of the lever in its circuit-closing position. Still further and also more detailed objects will 75 appear from the following specification and from the accompanying drawings, in which—

Fig. 1 is a front elevation of a switch embodying my invention in a type particularly 80 suited for use on the dashboard of automobiles.

Fig. 2 is a side elevation of the same.

Fig. 3 is a rear elevation of the same.

Fig. 4 is an enlarged central and longitudinal section through the switch of Fig. 1, showing the switching lever in its circuit-closing position.

Fig. 5 is a corresponding central section taken transversely of Fig. 4.

Fig. 6 is a central and longitudinal section through the switching lever, drawn on the same scale as Figs. 4 and 5.

Fig. 7 is an enlarged perspective view of one of the circuit terminal portions, showing the insulation-indenting fingers formed from the same.

Fig. 8 is a perspective view of the lower portion of the insulating base.

Fig. 9 is a similar perspective view of the upper portion of the said base.

Fig. 10 is a perspective view of the contact-plate which forms a part of one of the circuit terminals and which has a grooved portion arranged for guiding the contact 105 tip of the switching lever.

Fig. 11 is a fragmentary view showing another form of contact plate and guide means.

While the various features of my invention may be employed with substantially equal advantage in a variety of forms of switches and to some extent also in other electric fittings, my invention is particularly adapted for embodiment in a single-pole flush switch. I am therefore illustrating and describing the same in such an embodiment, although I do not wish to be limited to this particular use of the same.

In the drawings, the illustrated embodiment has a switch casing comprising a cylindrical wall 1 equipped with integral flanges 2 which are disposed behind a front plate 3, this front plate being desirably interlocked with the said flanges by two ferule-like formations 4 extending through corresponding perforations in the said flanges 2 and clinched over the back of the latter after the manner shown in Fig. 4. Secured to the rear end of the cylindrical side wall 1 is an insulating base which desirably is held in position by having its larger diameter rear portion 5 engaging the rear end of the cylinder 1 and by having fingers 6 formed from the rear end of the cylinder 1 and bent into recesses 7 in the rear base portion 5 so as to engage the rear face of the forward base portion 6.

These two base portions, which cooperate in affording an easily manufactured equivalent for a single-piece insulating base, are secured to each other by two posts 8 and 9 into which the wire-binding screws 10 are threaded, and one of the said screw receiving elements (namely the post 9) also serves for clamping to the base another circuit terminal part in the form of a contact plate 11 which has a part 12 extending towards the companion post 8, this part 12 being grooved for guiding the plunger tip or circuit-closing element 13 of the movable member of the switch. To facilitate the assembling of the parts for this purpose, I desirably form the rear base portion 5 of a disk of fiber or similar insulating material having a pair of perforations 14 each adapted to slidably receive the shank of one of the posts 15, and also having a pair of lateral notches 7 for housing the said clinching fingers 6 as formed from the side wall of the casing. Then I provide corresponding passageways for the said posts in the inner base members and desirably connect these passage-ways to each other by an elongated perforation portion after the manner shown in Fig. 9, so that the single composite perforation serves both for permitting the extending of the posts through this forward base member and for affording an elongated central recess disposed between the said posts. This central recess portion

serves for housing the contact portion 12 of the contact plate 11, which housed portion 12 is so formed as to be depressed into the said central recess when the parts are assembled as shown in Fig. 4.

For the movable switching member, I desirably employ a rocking lever having one end thereof resiliently mounted so as to make the lever yieldingly extensible, and I desirably insulate this yieldingly mounted portion from the main part of the lever. I also desirably provide the lever with a shoulder formation 24 engaging the rear face of a perforated boss 15 formed from the front plate 3 of the switch, through which boss the lever extends, so as to afford the needed pivotal mounting for the lever without requiring any shaft or any other auxiliary element for this purpose.

For example, Figs. 4 and 6 show the lever member as including a main metal lever portion 16 having at its forward end a knob 17 which affords a handle for manipulating the lever and having its rear end bored out to afford a cylinder 18 into which I slip or drive a cup 19 of insulating material. Inserted into this cup 19 is a guide cup 20, desirably made of metal and having its rear end contracted so as to afford a guide for a hollow plunger 13 which desirably has its tip rounded after the manner shown in the drawings. Interposed between this plunger 13 and the guide cup 20 is a compression spring 22, the tip or plunger part 13 being preferably hollowed out to receive a portion of this spring so as to permit a relatively long spring to be used.

When the parts are assembled, the plunger 13 bears against the groove plate portion 12 of the circuit terminal element 11 as shown in Figs. 4 and 5, the parts being so proportioned that the spring will be compressed during the assembling of the parts so that it will continuously tend to force the plunger 13 outwardly of its slidable mounting, or in other words will tend to extend the length of the lever. Thus assembled, and with the grooved plate portion 12 extending towards the terminal post 8 and the center of travel of the plunger 13 opposite the middle length of the plate 12 or along the axis of the boss 15, it will be evident from Fig. 4 that the lever will be effectively longer in its "on" and "off" positions (as shown respectively in full lines and in dotted lines in Fig. 4) than it would be at the center of its travel. Consequently, the spring 22 acts as a throw-over element and serves to hold the lever yieldingly either in its circuit-opening or circuit-closing position, in the latter of which the plunger or lever tip portion 13 directly engages the head of the terminal post 8. To make this contact all the more firm when the lever is in its circuit-closing position, I desirably increase the depth of

the grooved portion 12 of the contact plate adjacent to the free end of the latter, after the manner of Fig. 4, and also desirably provide this grooved plate portion with a pair 5 of flanges 23 engaging the forward face of the base member 6 at opposite sides of the recess in the latter so as to prevent this plate from being flexed by the thrust of the spring-pressed plunger. Then the edge of 10 the plate 11 which overhangs one end of the groove affords a stop for the lever during the "off" movement of the latter, as shown in dotted lines in Fig. 4.

With the parts thus arranged, it will be 15 obvious from the drawings that while the lever has its shoulder portion 24 socketed in the boss 15 with freedom for movement in any number of different planes, the grooved plate portion 12 affords a guide for 20 limiting the movement of the lever to a single plane, namely the plane of the center line of Fig. 1. The simple contact plate therefore serves both as a circuit terminal part continuously engaging the tip of the 25 lever and as means for determining the plane of movement of the lever without requiring a shaft or the like.

To prevent the posts 8 and 9 from rotating 30 when the wire-binding screws are tightened or loosened, and to insure an unmarred thread in these posts, I desirably construct each post initially of a plain cylinder having an enlarged flange or head at one end. Each such post is inserted first through one 35 end of the perforation in the forward base part 6 and then through the corresponding perforation 14 in the rear base part, and thereafter is clinched in position by forming a plurality of fingers 25 from the same 40 after the manner shown in Fig. 7. By employing outwardly turned fingers for this clinching instead of flaring out the entire rear end of the hollow post, I retain the cylindrical bore of the post for its entire 45 length with the exception of the relatively small recesses out of which the fingers 25 are formed. Consequently, the later tapping of the threads in the posts, which is 50 done after the posts together with the contact plate 11 have been secured to the two insulating base portions, produces threads adapted to afford a good grip for the corresponding wire-binding screws. Moreover, 55 by making the elongated central portion of the perforation in the base part 6 of a width corresponding to that between the flanges 23 on the contact plate, I cause the grooved part of this plate to engage the mouth of the recess afforded in the switch base by the said 60 perforation, thereby preventing this plate from shifting out of the position in which it limits the plunger of the lever to a path to and from the terminal post 8.

However, while I have illustrated and described my invention in a particular embodiment,

I do not wish to be limited to the details of construction and arrangement thus disclosed, it being obvious that the same might be modified in many ways without departing from the spirit of my invention 70 or from the appended claims. Neither do I wish to be limited to the use of all of the various novel features in combination with one another, since many of the same might obviously be employed separately or in other 75 connections, as for example by using my two-piece insulating base construction or my post construction on other electric appliances. For example, instead of forming the guide groove integral with the contact plate, 80 I may employ a contact plate 26, having a narrower portion continuously engaged by the plunger of the lever and may employ the sides of the recess in the insulating base as the means for laterally guiding this 85 plunger after the manner shown in Fig. 11.

I claim as my invention:—

1. A switch lever having a bore extending into the same from one end of the lever, a cup of insulating material disposed in the 90 said bore and having its mouth directed toward the said end, a cylinder within the cup, a shouldered plunger movable in the cylinder and having a tip projecting beyond all the aforesaid parts, the cylinder 95 having its outer end contracted to engage with the plunged shoulder, and a compression spring within the cylinder disposed for urging the plunger to increase the said projecting of its tip. 100

2. In a switch, a casing, a sectional insulating base in the casing having the rear section formed with peripheral notches, integral fingers on the casing engaged in the notches, posts extended through the sections to hold the latter together, the front section being engaged with the fingers and having a groove, a contact plate carried by one of the posts and having a part arranged in said groove, and a switching member having a tip in the groove and engageable with said contact plate. 105

3. In a switch, a casing having an insulating base formed with a groove, a contact plate having a part of concavo-convex cross-section, the convex face extending into the groove to hold the plate against movement laterally of the groove, and a universally mounted switching member having a spring tensioned tip projecting in the groove and engaged with the concave face of the contact plate, so as to have its movement restricted to the direction in which the groove extends. 115

4. In a switch, a casing having an insulating base, a universally mounted switching member having a tip carried by the casing, spaced circuit terminals carried by the base, and guiding means on the base arranged in the space between the terminals, 125 130

- and including a contact member spaced from one of the terminals and connected to the other, to guide the tip of the switching member in a path between said terminals, said tip in one position extending across said space between the contact member and the said terminal from which said contact member is spaced so as to engage said last named terminal.
10. 5. In a switch, a casing, an insulating member in the casing having a groove, a grooved contact member in the groove of the insulating member, binding posts carried by the insulating member and arranged in alinement with said groove of the insulating member, and a switching member having a tip movably engaged in the groove of the contact member and engageable with each of the binding posts so as to have its movement limited thereby.
15. 6. In a switch, a casing, a grooved insulating member in the casing, a contact member in the groove, binding posts carried by the insulating member and disposed adjacent to the groove ends, and a universally mounted switching member carried by the casing and having a tip engaged in the groove and with the contact member so as to have its movement restricted to the direction in which the groove extends.
20. 7. In a switch, an insulating base including two superposed parts one of which has a pair of spaced perforations and the other of which has a slot portions of which latter register with the respective pair of
25. 8. In a switch, a casing having an insulating base, a universally mounted switching member having a tip carried by the casing, spaced circuit terminals carried by the base, the base having a groove in the space between the terminals, and a contact member having a part extending into the groove and having one end connected to one terminal and the other end spaced from the other terminal, said tip being engageable with the contact member and in one position extending across said space between the contact member and said other terminal so as to engage the latter.
30. 9. In a switch, a casing, a grooved insulating base therein, a contact plate arranged in the groove and having a groove with an abutment at one end of the groove, contact terminals carried by the base, and a universally mounted switching member carried by the casing and having a part thereof engaged in the groove of the contact plate and with said abutment thereof.
35. Signed at Chicago, Illinois, June 13, 1922.
EDWARD S. PRESTON.
